US0D1094534S

(12) **United States Design Patent** (10) Patent No.: **US D1,094,534 S**
Blanc (45) Date of Patent: ** Sep. 23, 2025

(54) **PAYMENT TERMINAL**

(71) Applicant: **BANKS AND ACQUIRERS INTERNATIONAL HOLDING, Suresnes (FR)**

(72) Inventor: **Olivier Blanc**, Saint-Péray (FR)

(**) Term: **15 Years**

(21) Appl. No.: **35/521,466**

(22) Filed: **Dec. 22, 2023**

(80) **Hague Agreement Data**

Int. Filing Date: **Dec. 22, 2023**

Int. Reg. No.: **DM/234430**

Int. Reg. Date: **Dec. 22, 2023**

Int. Reg. Pub. Date: **Jun. 28, 2024**

(51) LOC (15) Cl. **18-01**

(52) U.S. Cl.

USPC **D18/4.6**

CN 304795298 * 8/2018

Primary Examiner — Marie D. Fast Horse

(57) **CLAIM**

The ornamental design for a payment terminal as shown and described.

DESCRIPTION

1. Payment terminal

1.1: Front

1.2: Left

1.3: Right

1.4: Top

1.5: Bottom

1.6: Perspective

1 Claim, 6 Drawing Sheets
